UNITED STATES PATENT OFFICE.

WILLIAM H. ENGLISH, OF DETROIT, MICHIGAN.

PERAMBULATOR.

SPECIFICATION forming part of Letters Patent No. 606,451, dated June 28, 1898.

Application filed February 14, 1898. Serial No. 670,201. (No model.)

To all whom it may concern:

Be it known that I, WILLIAM H. ENGLISH, a citizen of the United States, residing at Detroit, in the county of Wayne and State of Michigan, have invented certain new and useful Improvements in Perambulators, of which the following is a specification, reference being had therein to the accompanying drawings.

The invention consists in the construction 10 of a perambulator comprising a frame supporting wheels at its lower end, a hinged seat, and a hinged wheeled arm connected to the seat, so that the folding up of the seat or the arm will cause the folding of both.

15 The invention further consists in the construction, arrangement, and combination of the various parts, all as more fully hereinafter described.

In the drawings, Figure 1 is a perspective 20 view of a perambulator embodying my invention. Fig. 2 is a vertical central longitudinal section therethrough, showing in full and dotted lines the different positions of the folded parts.

25 It is well known that it is desirable at the present time to have perambulators which may be used on the street of such weight and having means for folding so that they may be carried into a car, as in most cities the 30 electric cars will not carry baby-carriages of the regular type. My invention is intended to supply that want and also for use in flats and other places where access to the street is difficult and where it would be impossible to 35 carry the ordinary baby-carriages up and down stairs. It is also used for ordinary use as a child's carriage.

A is a frame formed of side-bars and connecting-rods, having a handle B at the upper 40 end and wheels C at the lower end adapted to rest and run on the ground. To this main frame is hinged a seat-board D, preferably on one of the cross-bars, the outer end of that seat-board being supported by the links E, 45 connected to the arms F, which are pivotally connected to the sides of the frame and preferably slotted, as at a, for the purpose of more closely folding.

The links E have the extensions b below the 50 seat carrying the footboards c, pivoted thereto. Between the side-bars of the frame is pivoted the back G, the pivot-support being at the

lower end and the upper end being supported by a spring H, secured to the frame in any desired manner.

55 The spring has an adjustable connection with the back, as by means of the winged nut d on the bolt, which engages through the slot e in the spring, so that the back may be tilted forward or back, as desired, as plainly shown 60 in dotted lines, Fig. 2.

I is an arm hinged to the frame, preferably below the seat and preferably bifurcated to connect to the two side-bars, as plainly shown 65 in Fig. 1. At the lower end this bar is provided with the wheel or wheels J. The arm I is connected to the axle K of the front wheels by a folding link L, and the folding link is connected by means of the link M with the under part of the seat. The connection of 70 the link M to the seat is preferably through a rod O and the sliding sleeve P, so as to enable the parts to fold closer than they would otherwise with the construction shown. The sliding connection, however, is not necessary. 75 The rear end of the link L is provided with a slot Q for the same purpose; but, if desired, this may be omitted. I provide a canopy for the top, which may be of any suitable construction and is not shown, but is supported 80 upon an arm S, having a curved rear end T, provided with a slit U, through which it engages the bolt U' on the handle B, with a winged nut V' for clamping it in its adjusted position.

85 It is evident that by turning the arm S to any desired angle in relation to the frame the canopy will be raised over the seat.

The link L is provided with a rule-joint, so as to break up only and to lock it in its straight 90 position, so that the desirable way to fold the carriage up is to draw up on the seat, which will fold the link and draw in the arm I at the same time. It may be done, however, by striking the joint of the link L by the foot 95 and then pressing on the link I, which will fold up both parts.

What I claim as my invention is—

1. In a perambulator, the combination of the frame A having wheels at the lower end, 100 of a hinged seat, a rearwardly-extending hinged wheeled arm, a folding link connecting the arm to the stationary part of the frame and a connection from the folding link

to the seat whereby the folding of both the seat and the arm is effected by moving one.

2. In a perambulator the combination of the frame A having a wheeled axle at the lower end, of a rearwardly-inclined arm I pivoted to the frame and having a wheel or wheels at the lower end, a folding link having a rule-joint connecting the axle of the frame with the arm and the link connecting the folding link with the seat, whereby the drawing up of the seat will positively fold in the arm I, substantially as described.

3. In a perambulator, the combination of the frame A, the arm I pivoted thereto and extending rearwardly and downwardly there-

from having a wheel or wheels at its lower end, the folding link L connecting the arm with the axle K, the link having a slot connection with the arm I, the link M connecting the folding link with the seat and a bail or bar O on the seat with which the upper end of the link M has a sliding engagement, the parts arranged as and for the purpose described.

In testimony whereof I affix my signature 25 in presence of two witnesses.

WILLIAM H. ENGLISH.
